(57) **CLAIM**

The ornamental design for a pet harness, as shown and described.

DESCRIPTION

FIG. 1 is a front and bottom perspective view of a pet harness, showing my new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the pet harness, shown in an alternative position;

FIG. 10 is an enlarged perspective view of detail “10” identified in FIG. 2; and,

FIG. 11 is an enlarged perspective view of detail “11” identified in FIG. 4.

The dashed lines in the figures illustrate portions of the pet harness that form no part of the claimed design. The dash dot dash lines in FIGS. 2, 4, 10 and 11 are for the purpose of depicting the boundary lines of the enlarged views and form no part of the claimed design.

1 Claim, 11 Drawing Sheets
